(57) CLAIM

The ornamental design for a computer chassis, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a computer chassis with color on a front portion thereof, according to the present design; FIG. 2 is a front view of the computer chassis shown in FIG. 1, including color, according to the present design;

FIG. 3 is a rear view of the computer chassis shown in FIG. 1, according to the present design;

FIG. 4 is a right side view of the computer chassis shown in FIG. 1, according to the present design;

FIG. 5 is a left side view of the computer chassis shown in FIG. 1, according to the present design;

FIG. 6 is a top view of the computer chassis shown in FIG. 1, according to the present design; and, FIG. 7 is a bottom view of the computer chassis shown in FIG. 1, according to the present design.

The broken lines formed by dashes show portions of the computer chassis that form no part of the claimed design.

1 Claim, 7 Drawing Sheets
